UNITED STATES PATENT OFFICE.

WARREN P. LOUDON, OF SPRINGFIELD, MASSACHUSETTS, ASSIGNOR TO WESTINGHOUSE ELECTRIC & MANUFACTURING COMPANY, A CORPORATION OF PENNSYLVANIA.

AUTOMOBILE SWITCH.

Application filed June 5, 1922. Serial No. 566,034.

To all whom it may concern:

Be it known that I, WARREN P. LOUDON, a citizen of the United States, and a resident of Springfield, in the county of Hampden 5 and State of Massachusetts, have invented a new and useful Improvement in Automobile Switches, of which the following is a specification.

My invention relates to automobile 10 switches and is has particular relation to such switches as embody means for controlling the ignition circuits and lighting circuits of motor vehicles.

My invention has for one of its objects to 15 provide a mechanism of the character described above that may easily and conveniently be arranged to remain in any desired position.

A second object of my invention is to provide 20 a simple and compact mechanism for controlling a plurality of electrical circuits.

My invention comprises an arrangement for controlling a plurality of circuits in 25 which the actuating means therefor are rendered ineffective by a single controlling member. Two contact drums are provided with operating handles that are connected thereto by latching mechanisms. A single key-controlled member disconnects the 30 latching mechanisms from the contact drums when the latter are in desired predetermined conditions. The operation of the handles when the latching mechanisms are inoperative is not effective to change the 35 positions of the drums.

In the accompanying drawing,

Figure 1 is a front view in elevation of a 40 switch mechanism embodying my invention.

Fig. 2 is a view in longitudinal section of the mechanism of Fig. 1.

Fig. 3 is a view in transverse section taken on the line III—III of Fig. 2.

Fig. 4 is a front view of the switch mechanism of Fig. 1 with the cover removed.

The switch mechanism comprises a cylindrical casing member 1, a base plate 2 for supporting the various terminal members of the switch, a metallic cover plate 3 and a glass cover plate 4 that are retained in position by a ring 5. A contact drum 6 for controlling the ignition circuits and a contact drum 7 for controlling the lighting circuits of a vehicle are respectively mounted on a

shaft 8 and a hollow sleeve member 9 that are concentric with each other.

The contact drum 6 comprises an inner disk 10 that is mounted on the shaft 8 for rotation therewith and for rotation relatively to an outer ring member 11 which bears the usual contact segments. The disk 10 is provided with a latching mechanism comprising a radially movable member 12 having an extended portion 13 and a spring 14 for biasing the member 12 outwardly to engage the ring 11. The contact drum 7 similarly comprises an inner disk 16 that is rigidly secured to the sleeve member 9 and an outer ring member 17 that are connected by a latching mechanism comprising a reciprocable member 18 and a spring 19. Contact fingers 20 coact with the contact drums.

The latching mechanisms are controlled by a lock mechanism 21 of any usual or standard type. The lock mechanism comprises a rotatable member or key barrel 22 which has secured thereto a pin 23 that is eccentric relatively to the axis of the barrel. A reciprocable member 24 that is mounted in a suitable guide member 25 is provided with an arcuate slot 25^a with which the pin 23 coacts to constitute a cam mechanism.

The member 24 is provided at its upper portion with two oppositely extending arms 26 and 27, each of which is provided with upwardly projecting portions for coacting with the latch members 12 and 18, respectively. As best shown in Fig. 4, the member 27 is provided with a relatively long curved surface 28 that is adapted to engage the latch member 18 throughout a considerable range of movement of the contact drum 7. The projecting portion of the arm 26 is relatively narrow and is adapted to engage the latch member 12 in the "off" position only of the ignition contact drum 6.

As shown in Figs. 3 and 4, respectively, the respective ring members of the contact drums 6 and 7 are provided with suitable notches 29 in their peripheries that are adapted to be engaged by springs 30 and 31 for the purpose of yieldingly retaining them in any position to which they may be adjusted. The angle through which the contact drum 6 may be rotated is fixed by a slot 32 in the ring member 11 and a stop mem-

ber 33 that is secured to the base plate 2. The ring member of the contact drum 7 is provided with a slot 34 which coacts with a stop member 35 which appears in Figs. 2 and 4.

The drums 6 and 7 are controlled respectively by operating handles 37 and 38 which are rigidly connected to the shaft 8 and the sleeve member 9, respectively.

When it is desired to render the switch inoperative, such, for example, as upon parking the car, the ignition switch handle 37 is actuated to its "off" position. The lighting switch handle 38 may be in any of its several operative positions or its "off" position. The key barrel 22 is rotated by the usual key in a counter-clockwise direction, as viewed from the front, whereupon the cam mechanism comprising the pin 23 and the slot 26 actuates the slidable member 24 upwardly to disengage the latch members 12 and 18 from the respective ring members 11 and 17. The latter members are retained in the positions to which they have been adjusted by the springs 30 and 31.

The operation of the handles 37 and 38 is not effective to change the positions of ring members 11 and 17 of the drums 6 and 7, respectively, since the corresponding disks 10 and 16 are disconnected therefrom. If either of the handles 37 and 38 has been actuated from its normal position relatively to its corresponding drum subsequent to its disconnection therefrom, it will be necessary, after the release of the latching mechanisms, to return it to such position in order that the latch member may register with the coacting slot in the corresponding members when the key is operated to render the switch mechanism adjusted.

In order to insure that the ignition contact drum 6 is in its "off" position when the latching mechanisms are disengaged, the ring member 11 is provided with a slot 39 into which the extension 13 projects and which must register with the member 26 before the latching mechanisms may be released. In case the ignition switch is in other than its "off" position, the member 26 engages the periphery of the ring member 11 and upward movement of the member 24 is thereby prevented.

The advantages obtained by employing a switch constructed in accordance with my invention are that the parts are comparatively few in number, may be easily assembled and occupy a comparatively small space. The arrangement whereby the operating handles are disconnected from the contact drums instead of being locked in their adjusted positions prevents an unauthorized person from rendering the switch operative by breaking the locking mechanism upon application of relatively great force to the operating handles, as is possi-

ble in connection with switches of certain types of standard construction. The rotation of the handles of a switch such as that described herein cannot operate to change the position of the contact drums so long as the key controlled mechanism occupies the position in which the latching mechanisms are disengaged.

I claim as my invention:

1. A switch comprising two rotatable members, a plurality of coacting members, an actuating member for each rotatable member and a single key-controlled member for controlling the operative connection of said actuating members to the respective rotatable members.

2. A switch comprising two rotatable drums, actuating handles therefor and a key-controlled member for simultaneously effecting the disconnection of said drums from said handles.

3. A switch comprising two rotatable drums, actuating handles therefor, latching mechanisms for connecting said handles to said drums and a single member for simultaneously controlling the latching mechanisms.

4. A switch comprising two contact drums in axial alignment, two concentric shafts for actuating said drums, a latching mechanism for connecting said shafts to the respective drums, and a member for selectively rendering said latching mechanisms operative or inoperative.

5. A switch comprising two contact drums in axial alignment, two concentric shafts for actuating said drums, a latching mechanism for connecting said shafts to the respective drums, and a member for selectively rendering said latching mechanisms operative or inoperative when one of said drums is in one position only and when the other of said drums is in any position.

6. A switch comprising an ignition controlling member having an "off" and an "on" position, a lighting controlling member having a plurality of operative positions and an inoperative position, actuating means for each of said controlling members, and means for rendering said actuating means ineffective when said ignition controlling member is in its "off" position only and said lighting controlling member is in any position.

7. A switch comprising an ignition controlling member having an "off" and an "on" position, a lighting controlling member having a plurality of operative positions and an inoperative position, actuating means for each of said controlling members, latching means for connecting the actuating means to the respective controlling members, and means for rendering said latching means inoperative, said last-named means being effective only when said ignition controlling member is in its "off" position.

8. A switch comprising two rotatable contact members, two shafts for actuating the respective contact members, a spring-actuating latch member for operatively connecting each shaft to the corresponding contact member, and means for controlling the latch members comprising a key-actuated member and a cam mechanism controlled thereby.
9. A switch comprising two rotatable contact members, two shafts for actuating the respective contact members, a spring-actuated latch member for operatively connecting each shaft to the corresponding contact member, and means for controlling the latch members comprising a reciprocable member for actuating them out of engagement with said contact members and a rotatable member for actuating said reciprocable member.
10. A switch comprising two rotatable contact members, two shafts for actuating the respective contact members, a spring-actuated latch member for operatively connecting each shaft to the corresponding contact member, and means for controlling the latch members comprising a reciprocable member, one of said contact members being arranged to permit the operation of said reciprocable member only when said one contact member occupies a predetermined position.
11. A switch comprising two rotatable contact members, two shafts for actuating the respective contact members, a spring-actuated latch member for operatively connecting each shaft to the corresponding contact member, and means for controlling the latch members comprising a reciprocable member, one of said contact members being arranged to permit the operation of said reciprocable member only when said one contact member occupies a predetermined position.

In testimony whereof, I have hereunto subscribed my name this 25th day of May, 1922.

WARREN P. LOUDON.
